UNITED STATES PATENT OFFICE.

EDGAR B. BROOKS, OF LA PORTE, INDIANA.

WATER-WHEEL.

SPECIFICATION forming part of Letters Patent No. 224,270, dated February 10, 1880.

Application filed November 8, 1879.

To all whom it may concern:

Be it known that I, EDGAR B. BROOKS, of the city and county of La Porte, in the State of Indiana, have invented certain new and useful Improvements in Water-Wheels, of which the following is a specification.

It is a fact well known to those skilled in such matters that turbine water-wheels having adjustable feed-chutes or sluiceways, whereby 10 the water is shut off or its volume regulated, are defective, because it is not practicable to make the sluiceways so that they will remain tight and shut off the water perfectly for any 15 length of time, and it is very difficult to make them tight at the start. The number of the parts and the wear upon them make it impracticable to secure good results for more than a limited period when the wheel is new. This 20 is a serious defect, because the adjustable chutes are the best for use when anything less than a full head of water is employed, it being a well-understood fact attending the use of the cylinder-gate that when a portion of the 25 water is shut off the power is decreased in a very much greater ratio than the portion of water cut off warrants.

My invention, which is designed to overcome this evil, consists in combining with the adjustable-chute water-wheel a cylinder-gate for 30 the purpose of cutting off the water when the wheel is to be stopped, and relieving the chutes of the performance of that function, the result being that it becomes wholly unnecessary to make the chutes tight, and any 35 looseness imparted to them by wear becomes immaterial instead of an injury, as heretofore.

The invention also consists in certain details of construction, which will be fully explained below.

40 In the accompanying drawings, Figure 1 is a side elevation of my improved wheel. Fig. 2 is a central vertical section thereof; and Figs. 3 and 4 are, respectively, a plan view and horizontal section of the same. Fig. 2 is taken upon the line xx of Fig. 3, and Fig. 4 upon the line yy of Figs. 1 and 2. Fig. 5 is a detail section of the sleeve-bearing for the wheel-shaft, and is taken upon the line zz of Figs. 1 and 2.

45 In the drawings, A represents the ordinary turbine wheel carried upon a shaft, A', which

is supported upon a pivot, A², at the bottom, and is provided with a coupling, A³, at the top, whereby it is connected to the machinery to be operated. B is the usual inclosing-shell. 55

The wheel-shaft is encircled, both above and below the shell, by a sleeve, B' B², and upon the upper end of this sleeve is an adjustable bearing, B³, composed of three parts, b³, adjustable toward the shaft by means of the 60 screws b⁴, as will be clearly understood from the detail, Fig. 5.

Mounted upon the bearing B³ is a horizontal shaft, C, carrying pinions C' and a hand-wheel, C², for operating the same. These pinions engage each with a rack upon the upper ends of rods C³, which extend down through the shell and sustain the cylinder-gate D. By means of these pinions and racks the gate is raised and lowered, as desired, within the 70 shell, and the part of the sleeve marked B' is made to extend below the range of movement of the cylinder, so it may serve as a guide therefor. 65

In Fig. 2 the gate is shown as lowered to 75 the position it occupies when used to cut off the flow of water, and it then rests upon the inward projection of bottom E of the feed-chutes.

The feed-chutes are formed between the rim 80 E' at the bottom of the shell and the bottom E, already mentioned, which is a horizontal annular rim upon the top of the outlet-skirt F, stationary sides E³, and adjustable sides E⁴. The parts E⁴ are pivoted upon pivots e at their 85 inner ends, and their free ends are swung outward in the direction of the arrows by means of arms e', carried by a sliding collar, e², encircling the shell and riding upon a ledge, e³, and operated by a rack, e⁴, and pinion e⁵, the latter 90 being mounted upon a vertical shaft extending to a point where it can be reached and turned by the hand of the operator, such shaft not being shown because it is not deemed necessary. 95

In Fig. 4 the chutes are shown as entirely closed; but in practice it is unnecessary to thus close them, because the gate shuts off the water without their assistance. The outlet is flaring at the bottom, as shown. This enables the water to spread as soon as it leaves the wheel, and thereby to avoid giving any 100

back shock to the machinery. The pivot which supports the wheel-shaft is borne by arms extending across the bottom of the outlet.

By supporting the gate-operating devices upon the sleeve I am enabled to apply the lifting power to the gate very near the center and avoid friction in the operation. It also makes a very economical and simple construction.

10 I claim—

1. The combination, with a water-wheel having adjustable feed-chutes, of a cylinder-gate, substantially as described, and for the purpose specified.

2. The combination, with a water-wheel, of 15 an inclosing-shell, a sleeve around the shaft and extending up from the shell, a cylinder-gate within the shell, and a rack-and-pinion device for raising and lowering the gate supported upon said sleeve, substantially as specified. 20

EDGAR B. BROOKS.
